(57) **CLAIM**

I claim the ornamental design for the all terrain vehicle, as
shown and described.

DESCRIPTION

I further expressly incorporate by reference the specification
and drawings of the following related applications: (1) U.S.
patent application Ser. No. 12/069,515 filed Feb. 11, 2008,
titled “Drivetrain for an All Terrain Vehicle”; (2) U.S. patent
application Ser. No. 12/069,511 filed Feb. 11, 2008, titled
“Frame for an All Terrain Vehicle”; and (3) U.S. patent applica-
tion Ser. No. 12/069,521 filed Feb. 11, 2008, titled “Sus-
pension for an All Terrain Vehicle,” the disclosures of which
are expressly incorporated by reference herein.

FIG. 1 is a perspective view of the all terrain vehicle of the
present invention;

FIG. 2 shows a left side view of the all terrain vehicle of FIG.
1;

FIG. 3 shows a right side view of the all terrain vehicle of FIG.
1;

FIG. 4 shows a top view of the all terrain vehicle of FIG. 1;
FIG. 5 shows a bottom view of the all terrain vehicle of FIG.
1;

FIG. 6 shows a front view of the all terrain vehicle of FIG. 1;
and,

FIG. 7 shows a back view of the all terrain vehicle of FIG. 1.
The portions of the all terrain vehicle shown in broken lines
form no part of the claimed design.
